UNITED STATES PATENT OFFICE.

FRANK F. KRAUSE, OF MANSFIELD, WASHINGTON.

WATER-COOLING PUMP FOR INTERNAL-COMBUSTION ENGINES.

1,359,389.

Specification of Letters Patent. Patented Nov. 16, 1920.

Application filed July 14, 1919. Serial No. 310,689.

To all whom it may concern:

Be it known that I, FRANK F. KRAUSE, a citizen of the United States, residing at Mansfield, in the county of Douglas and State of Washington, have invented certain new and useful Improvements in Water-Cooling Pumps for Internal-Combustion Engines, of which the following is a specification.

10 This invention relates to a pump or impelling device particularly designed for use in the fluid circulating system, such as the cooling system of internal combustion engines, and an object of the invention is to provide means whereby air may be drawn into and mixed with the cooling liquid of the cooling system of an internal combustion engine or analogous structure.

Another object of the invention is to provide a device as specified, for facilitating the cooling of an internal combustion engine or analogous structure, means comprising a propeller rotatable by the fan belt of the power plant of a motor vehicle or otherwise 25 suitably rotatable, the supporting shaft of which is hollow, the said hollow opening out through opening means placed in the propeller, which blades are positioned in the path of the cooling fluid and impel or agitate the cooling fluid to increase its active movement, and which impelling of the fluid will have a tendency to create a suction through the hollow supporting shaft and blades of the propeller for drawing air 30 therethrough, for intermingling or mixing with the water and consequently cooling the same.

A further object of the invention is to provide a valve structure for cutting off the 40 supply of air to and through the hollow supporting shaft of the propeller which is connected to the propelling shaft by a flexible hose structure to eliminate the transfer of vibration from the shaft to the valve during 45 operation of the device.

Other objects of the invention will appear from the following detailed description taken in connection with the accompanying drawings, forming a part of this specification, and in which drawings:

Figure 1 is a side elevation of the improved pump showing the same applied to a fragment of the power plant of a motor vehicle.

55 Fig. 2 is a longitudinal section through the pump structure.

Fig. 3 is a cross section through the pump structure taken on the line 3—3 of Fig. 2, and on an enlarged scale.

Fig. 4 is a section through the propeller 60 taken on the line 4—4 of Fig. 3.

Fig. 5 is a detail section illustrating the inlet of the air supplying hose or pipe, and

Fig. 6 is a detail section through the valve for controlling the supplying of air to the 65 hollow propeller carrying shaft.

Referring more particularly to the drawings, wherein like characters indicate like and corresponding parts throughout the several views, A indicates an ordinary internal 70 combustion engine of the power plant of the motor vehicle, and while the improved pump or impelling structure is particularly designed for use in connection with motor vehicles, it is applicable for use in connection 75 with stationary internal combustion engines or several other analogous structures, and it is to be understood that the device may be used with any structure, with which it will perform its proper function without departing from the spirit of this invention.

The radiator B of the cooling system of the internal combustion engine A is of the usual construction and the lower or outlet end of the said radiator has communication 85 with the water jacket of the engine through the usual pipe C. However, a relatively large cylinder or pipe 10 is provided, which is attached to the engine A and has communication with the pipe C through a 90 branch pipe 11. The cylindrical pipe 10 has a closure plug 12 mounted in one end thereof, which carries a relatively long bearing 13, projecting into the pipe 10 and a second bearing 14 projecting outwardly out of the 95 pipe which carries a packing washer structure 15 for forming a fluid tight joint about the hollow shaft 16. The hollow shaft 16 is rotatably supported by the bearing 13 and has a collar 17 thereon, for engagement 100 against the inner end of the bearing 13 to prevent longitudinal movement of the shaft. The shaft 16 is hollow, being provided with an axial bore 18, which opens out through ways 19 in plane of the propellers 20. The 105 propellers 20 are formed upon or mounted upon the end of the hollow shaft 16 and is positioned within the pipe 10 sufficient distance beyond the communication between the pipe and the branch 11 to prevent back 110 action of the cooling fluid into the pipe 11.

The ways 19 in the propeller blade open

at the following faces of the blade so that the cooling fluid agitated or impelled by rotation of the propeller 20 will create a suction through the hollow shaft 16. An elbow 21 is connected to the outer end of the hollow shaft 16 and rotatably receives said outer end of the shaft, which elbow is braced and supported by a suitable bracing structure 22. A pipe 23 communicates with the elbow 21. However, a flexible hose may be employed in lieu of the pipe. This flexible conduit 23 has communication with the casing 24 of a valve structure 25. The valve structure 25 is supported in any suitable manner, upon the engine structure A and the slidable gate 26 thereof is normally urged into an open position by means of a spiral spring 27. A flexible shaft or wire 28 is connected to the gate 26 and is adapted to extend to the dash of the motor vehicle or to any other place where it may be conveniently operated for controlling the passage of air through the valve casing 24 and consequently through the conduit 23. A second conduit 29 communicates with the inlet end of the valve casing or housing 24 and it also communicates with the interior of a substantially inverted conical guard 30 formed by a plate 31, which is preferably soldered or otherwise suitably attached to the radiator structure B at the top thereof, to permit relatively cool air to be sucked into and through the conduit 29 and through the valve structure 25, the conduit 23 to be drawn through the propeller 20 and intermingled with the cooling fluid in the pipe 10.

The hollow shaft 16 of the propeller structure has a pulley 32 mounted thereon and preferably connected to the shaft for rotating it by means of a set screw 33, thereby permitting limiting adjustment of the pulley longitudinally upon the shaft to accommodate various types of motor vehicles, or power plants. This pulley 32 is adapted to have rotation imparted thereto from the usual fan mechanism 34, of the power plant or motor A, through the medium of a belt 35. However, it is to be understood that the pulley 32 may be operatively connected to any desired propelling means for rotating it and consequently rotating the shaft 16 and the propeller structure 20.

Changes in details may be made without departing from the spirit of this invention, but; I claim:

1. The combination with the cooling system of an internal combustion engine, of a propeller rotatable in the cooling liquid to circulate the same, and means for conducting air into the liquid adjacent the blades of said propeller.

2. The combination with a fluid conduit, of a fluid-impelling device comprising a hollow shaft extending into said conduit

and having atmospherical communication, a propeller within said conduit mounted on said shaft and having ways therein communicating with the bore of the shaft and opening out through the blades of the propeller into the conduit whereby air will be drawn into the conduit upon rotation of the propeller and means upon the shaft operable to rotate the shaft and propeller.

3. The combination with a fluid conduit, of a fluid-impelling device comprising a hollow shaft extending into said conduit and having atmospherical communication, a propeller within said conduit mounted on said shaft and having ways therein communicating with the bore of the shaft and opening out through the blades of the propeller into the conduit whereby air will be drawn into the conduit upon rotation of the propeller and means upon the shaft operable to rotate the shaft and propeller, the ways in said propeller blades opening at the following faces thereof whereby a suction will be created through the shaft during rotation of the propeller.

4. The combination with a fluid conduit, of a fluid-impelling device comprising a hollow shaft extending into said conduit and having atmospherical communication, a propeller within said conduit, mounted on said shaft and having ways therein communicating with the bore of the shaft and opening out through the blades of the propeller into the conduit whereby air will be drawn into the conduit upon rotation of the propeller and means upon the shaft operable to rotate the shaft and propeller, the ways in said propeller blades opening at the following faces thereof whereby a suction will be created through the shaft during rotation of the propeller, and a valve for controlling the inlet of air into said hollow shaft.

5. The combination with the water cooling chamber of an internal combustion engine, and the water supply pipe therefor, of a pipe having communication with said supply pipe and with the interior of said jacket, a hollow shaft rotatably supported by and extending into said pipe, a propeller within said second mentioned pipe, mounted on said shaft and having ways therein communicating with the bore of the hollow shaft and opening out through the blade into the conduit for creating a suction through the blades and hollow shafts upon rotation of the propeller to draw air into the pipe, said hollow shaft projecting out of said pipe, and means upon the outer end of the shaft operable to revolve said shaft and propeller.

6. The combination with the water cooling chamber of an internal combustion engine, and the water supply pipe therefor, of a pipe having communication with said supply pipe and with the interior of said jacket,

a hollow shaft rotatably supported by and extending into said pipe, a propeller within said second mentioned pipe, mounted on said shaft and having ways therein communicating with the bore of the hollow shaft and opening out through the blade into the conduit for creating a suction through the blades and hollow shafts upon rotation of the propeller to draw air into

- 5 the pipe, said hollow shaft projecting out of said pipe, means upon the outer end of the shaft operable to revolve said shaft and propeller, a conduit connected to the outer end of said hollow shaft, a valve interposed in
10 15 said conduit for controlling the passage of air through the conduit and said hollow shaft.

7. The combination with an internal combustion engine having a water cooling chamber, and a water supply pipe therefor, of a pipe attached to the engine and having communication with the water cooling chamber and supply pipe, a fluid-impelling device, including a hollow shaft rotatably supported by said pipe and extending thereinto, a propeller within said second mentioned pipe, mounted on said shaft and rotatable about an axis parallel with the axis of the pipe, and means adjustably mounted upon the outer end of the said shaft and operable to 30 35 40 45 50 rotate the shaft and propeller.

FRANK F. KRAUSE.
